UNITED STATES PATENT OFFICE.

GEORGE HASECOSTER, OF RICHMOND, INDIANA, ASSIGNOR TO J. M.
HUTTON & CO., OF SAME PLACE.

DESIGN FOR BURIAL-CASKETS.

Specification forming part of Design No. 5,838, dated May 7, 1872.

Specification describing a new and original Design for a Burial-Casket, invented by GEORGE HASECOSTER, of Richmond, in the county of Wayne and State of Indiana.

According to my design I provide both the sides and ends of the coffin with a panel formed by means of a raised bead or ovolو molding, which is ornamented or flourished at the corners. The panels correspond in form with the respective parts to which they are applied, and the bead is in each case near the edge, so that the panels are relatively large. The corners of the coffin are essentially right-angled, but rounded slightly, as shown. A

band composed of a suit of three scotia-shaped, equal-width moldings, encircles the raised portion *a* of the lid or cover *A*, and otherwise the latter is made to correspond with the body of the coffin as far as practicable.

I claim as my invention—

The design for a burial-casket, provided with the panels formed by a molding flourished at the corners, and a cover having three equal-width moldings, substantially as described.

GEORGE HASECOSTER.
